ATTORNEY

UNITED STATES PATENT OFFICE

HERMAN W. SITTIG, OF YOUNGSTOWN, OHIO

SCAFFOLD BRACKET

Application filed March 16, 1929. Serial No. 347,594.

This invention relates to scaffold brackets. The principal object of this invention is to provide a scaffold bracket which is safe and easily put into use and removed when not in use.

A further object of the invention is to provide a scaffold bracket that may be folded when not in use.

A further object is to provide a scaffold bracket that may be put in position in the construction of a building without cutting or leaving holes in the sheathing in order to place a scaffold bracket in position.

A still further object is to provide a device with a locking brace member which provides a means for enabling the bracket to be folded when not in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein:—

Figure 1 is a top plan view of the device in position with reference to a wall.

Figure 2 is a side elevation in position with reference to a wall.

Figure 3 is a detailed sectional view taken on line 3—3 of Figure 2.

Figure 4 is a view of the device when folded.

By referring to the drawings, it will be seen that I have shown a studding 1. In ordinary building construction sheathing 2 is nailed or secured to the studding 1. At positions on the wall where it is desired to place the scaffold bracket, the sheathing 2 is placed so as to leave a slight opening 3 for the insertion of a securing hook 4 which functions with the studding 1. It will be seen by referring to Figure 2 that this securing hook 4 is an extension of an upper portion 5 of an angle iron 6, which forms the horizontal rest for staging planks 7, upon

which workmen may stand. It will also be seen that at the extreme outer end 8 of the angle iron 6 I have provided an upright 9 which is formed by cutting and turning up from a horizontal to a vertical position the outer end of the upper portion 5. This upright 9 is utilized to prevent the staging planks 7 from slipping outwardly beyond the extreme outer end 8 of the angle iron 6. Hinged to this angle iron 6 by means of a pivot pin 10, I have provided a vertical angle iron 11 which is provided with a curved upper end 12. The opening of this curved upper end 12 is to provide space sufficient to push the securing hook 4 so that it may function with a stud 1, when the device is in a folded position as shown in Figure 4. It will also be seen that this angle iron member 11 is provided with a plate 13 which is secured by means of rivets 14 in order to prevent the scaffold bracket when in position from undesired horizontal movement.

In order to hold the angle iron 6 at right angles to the vertical angle iron 11, I have provided a locking brace member consisting of parts 15 and 16. These parts 15 and 16 are formed of angle iron. The part 15 is secured at an upper end 17 to the angle iron 6 by means of a pivot pin 18 at point 19. The part 16 is secured to a vertical angle member 11 by means of a pivot pin 20 at point 21. The inner ends of the parts 15 and 16 are hinged so that they may be folded when not in use. In order to do this I have provided a slot 22 formed in the part 15 through which functions a slidable bolt or pivot pin 23 which is secured to an inner end 24 of the part 16. The extreme inner end 25 of the part 15 is bifurcated providing means for functioning with lug 26 which is secured to the part 16 at point 27. It will also be seen that the inner end of the part 15 is provided with a dependent flange 28 which functions with an outer edge 29 of the part 16, in order to hold the assembled parts 15 and 16 in rigid alignment in reference to each other.

In folding up the device, the extreme outer end 8 is lifted up thus allowing the part 15 to free the bifurcated end 25, lug 26 so

that these parts may be folded inwardly towards the parts to which the outer ends of the same are hinged. By referring to Figure 3, it will be seen that there has been 5 provided a notch 30 which is formed on the part 15 in such a position that when the part 15 is folded up against the part 16 the lug 26 functions within the notch 30.

By referring to Figure 2, it will be seen 10 that at a point where the securing hook passes through the opening 3, it is slightly thicker in order to provide against possibility of bending or breaking at this point when under strain.

15 What I claim is:—

1. In a collapsible scaffold bracket a vertical angle iron having a curved upper portion, a horizontal angle iron having its inner end pivoted to said vertical angle iron 20 and an extension at its outer end forming a securing hook, a two-part locking brace member, a pin pivotally securing the inner ends of said brace member parts, one of said brace member parts having a slot slidably 25 engaged by said pin, and a lug adjacent the inner end of the other brace member part, the first named brace member part having a bifurcated end adapted to engage the lug to hold the brace member parts in locked 30 position when the device is opened in position for use.

2. In a device of the class described, a vertical member having a curved upper end, a horizontal member pivoted to said curved 35 end, a securing hook member formed as an extension of said horizontal member for the purpose of engaging a studding or upright of a building, a two-part lock brace member pivoted to the outer end of said horizontal 40 member and to the lower-end of said vertical member, a pin pivotally connecting the parts of said brace member, one of said parts having a slot, a flange and a bifurcated end and the other part having a lug to engage in said bifurcated end, said pin, slot, flange, 45 lug and bifurcated end cooperating to lock the brace parts in an extended and aligned position.

In testimony whereof I affix my signature.

50 HERMAN W. SITTIG.
